UNITED STATES PATENT OFFICE.

MARGUERITE A. BUCHWALTER, OF NEW YORK, N. Y.

DESIGN FOR A CANDLESTICK OR SIMILAR ARTICLE.

Application filed October 15, 1928. Serial No. 28,487. Term of patent 7 years.

To all whom it may concern:

Be it known that I, MARGUERITE A. BUCHWALTER, a citizen of the United States, residing at New York city, county and State of New York, have invented a new, original, and ornamental Design for Candlestick or Similar Article, of which the following is a specification, reference being had to the accompanying drawing, forming part thereof.

What I claim is:

The ornamental design for a candlestick or similar article substantially as shown.

MARGUERITE A. BUCHWALTER.
